UNITED STATES PATENT OFFICE.

WILLIAM CHAS. ROE, OF PITTSBURGH, PENNSYLVANIA, ASSIGNOR TO KNOX PRESSED & WELDED STEEL COMPANY, OF PITTSBURGH, PENNSYLVANIA, A CORPORATION OF PENNSYLVANIA.

REVERSING MECHANISM FOR REGENERATIVE REVERSING-FURNACES.

1,096,197.

Specification of Letters Patent.

Patented May 12, 1914.

Application filed April 19, 1913. Serial No. 762,232.

To all whom it may concern:

Be it known that I, WILLIAM C. ROE, a citizen of the United States, residing at Pittsburgh, in the county of Allegheny and 5 State of Pennsylvania, have invented a new and useful Improvement in Reversing Mechanism for Regenerative Reversing-Furnaces, of which the following is a full, clear, and exact description, reference being had 10 to the accompanying drawings, forming part of this specification, in which:—

Figure 1 is a view partly in plan, partly in horizontal section and largely conventional of mechanism embodying my invention; Fig. 2 is a sectional elevation of the same; Fig. 3 is a plan view of a portion of the operating mechanism; Fig. 4 is a side elevation of the same with a part of the motor shown in section; and Fig. 5 is an end 20 view of the mechanism shown in Fig. 3.

My invention has relation to reversing mechanism for regenerative reversing furnaces, and is designed to provide means of simple, convenient and efficient character, 25 whereby the various operations of the gas and air valves necessary to completely reverse a furnace of this type can be effected by the operation of a single motor.

The nature of my invention will be best 30 understood by reference to the accompanying drawings, in which I have shown the preferred embodiment thereof and which will now be described, it being premised, however, that various changes may be made 35 in the details of construction and arrangement of the several parts, without departing from the spirit and scope of my invention as defined in the appended claims.

In these drawings, the numerals 2 and 3 40 designate right and left hand gas ports leading from a valve chamber 4 to the furnace regenerators, not shown.

5 is the gas admission port, and 6 and 7 are the two air ports leading to the regenerators. Each of these ports is provided 45 with a vertically movable air inlet valve, that for the right hand port being designated 8, and the one for the left hand port being shown at 9.

10 is a port leading to the stack and communicating with the ports 6 and 7.

11 is a port leading from the gas-reversing valve chamber 4 to the stack.

The numeral 12 designates a vertically

movable damper which is placed between 55 the valve 9 and the point of communication of the port 6 with the port 10. 13 is a similar damper which is placed between the valve 8 and the point of communication between the ports 7 and 10.

14 designates a gas-reversing valve, and 15 a cruciform shaped seat therefor located in the chamber 4. The valve 14 is of the type which, in order to be operated, is first lifted out of a bottom bearing, such as 65 shown at 15, Fig. 2, and is then rotated through an angle of approximately ninety degrees.

In the position of the ports shown in Figs. 1 and 2, gas enters the port 5 and passes 70 through one side of the chamber 4 into the left hand regenerator port 3. The return from the furnace is through the port 2 and through the opposite side of the chamber 4 to the stack port 11. The valve 8 being 75 open, damper 13 being closed, damper 12 being open, and valve 9 being closed, air will enter the port 7 through the valve 8, the return being by way of port 6 into the stack through port 10, which is at a lower 80 level than the gas port 5 and stack connection 11.

The flue, valve and damper arrangement just described forms no part of my invention, which is concerned with operating 85 mechanism for the valves 8, 9 and 14 and the dampers 12 and 13. This operating mechanism will now be described.

The numeral 16 designates a double-acting power cylinder whose piston or plunger 90 rod 17 is detachably connected at 18 with one end portion of a reciprocable rack bar 19. The teeth of this rack bar mesh with the teeth of a pinion 20, mounted on the transverse shaft 21, to which is also secured 95 a pulley 22. The rack 19 is held in engagement with the teeth of the pinion 20 by any suitable means, such as the top bearing roller 23.

24 is a vertical extension of the shaft of 100 the gas-reversing valve 14. Secured to this extension is a pulley 25. 26 is a crank arm also secured to the shaft extension 24. This crank arm is of alligator-jaw form, the two jaws being designated 26^a and 26^b and being adapted to be engaged by an antifriction roller 27 on the rack bar 19. Also secured 105 to the transverse shaft 21 is a cam having a

2
low portion 28 and a high portion 29. This cam is arranged to act upon an antifriction roller 30, mounted on one arm of a lever 31 fulcrumed at 32. The other arm of this lever is forked, as shown at 33, and engages the flange 34 of a lifting sleeve 35, loosely mounted on the shaft extension 24. Anti-friction bearings 36 are preferably interposed between the upper end of this sleeve and the lower end of the hub portion of the crank 26.

5 A rope or cable 37 is interposed around the pulley 25 and one end portion is carried over a pulley 38, and thence downwardly to the air inlet valve 8, to which its lower end is connected. The other end portion of the rope or cable 37 is carried over a similar pulley 39, and thence downwardly to the air inlet valve 9. A second rope or cable 40 is 10 passed around the pulley 22 on the shaft 21, with one end portion passing over suitable idlers 41, and thence downwardly to the damper 13, to which it is connected, the other end portion of the rope or cable 40 15 passing over similar pulleys 42, and being connected to the vertically movable damper 12.

20 The operation is as follows: Assuming the parts to be in the position shown in Figs. 3, 30 4 and 5, the motive cylinder 15 is operated to force its rod or plunger 16 to the right. This effects the rotation of the shaft 21 and thereby of the pulley 22. The rotation of the pulley 22 operates the rope or cable 41, thereby closing the damper 12 and opening the damper 13. During this first period of 35 rotation of the shaft 21, the cam on said shaft has been rotated to bring its high portion 21 on to the roller 30 of the lever 31. 40 This actuates said lever to lift the shaft 24 and thereby the valve 14. During this time, the roller 27 on the rack bar 19 has been moving idly on the face of the jaw 26 of the crank 26. When, however, the valve has 45 been raised in the manner described (which occurs during the first quarter of the stroke of the valve bar) this roller 27 passes into the recessed angle between the inner faces of the two jaws and into engaging contact 50 with the face of the jaw 26^b, and during the middle portion of the stroke, the shaft extension 24 on the valve is turned through an angle of approximately ninety degrees. During this last period of movement, the 55 high portion 29 of the cam remains on the roller 30, holding the valve 14 in its raised position while it is being turned. During the last quarter of the stroke, the low portion of the cam 29 comes on the roller 30 and 60 thus effects the lowering of the valve 14. It will be noted that the roller 27 acts effectively as a stop at all times to prevent movement of the valve 14, except during its reversal by the action of the cylinder 16. The 65 rotation of the shaft 24 through the pulley

25 acts to close the air valve 8 and open the air valve 9.

It will be apparent that a single stroke of the motor effects all the operations necessary to make the complete reversal of the furnace. The parts remain in the positions in which they are left at the close of the operations just described until it is desired to again reverse the furnace. The cylinder 16 is then operated in the reverse direction. 75 This repeats the cycle of operations, but in the reverse manner.

80 The mechanism is extremely simple in its construction and arrangement; is not likely to get out of order, or if it does, can be readily repaired; and enables the furnace attendant, by the operation of a single valve controlling the motive cylinder 16, to reverse the furnace at will.

I claim:

85 1. The combination of a gas-reversing valve arranged to be lifted and then rotated, two air valves arranged to be simultaneously operated in opposite directions and dampers also arranged to be reversely operated, of a single motive device, connections actuated by said device for operating said valve and dampers, lifting means also operated by said device for first raising the valve, and other means also operated by said device 90 for subsequently rotating the valve, substantially as described.

95 2. The combination with a gas-reversing valve mounted to be lifted, then rotated, and then dropped back to its seat, and with two 100 dampers and two air valves of which one damper and one air valve are to be opened simultaneously with the closing of the other damper and air valve, of a single motive device, connections operated by said device 105 for first raising the reversing valve and then rotating it, and connections operated by the rotation of the said valve for simultaneously closing one air valve and opening the other, and other connections operated by the motive device for simultaneously opening one 110 damper and closing the other, substantially as described.

115 3. The combination with a gas-reversing valve, mounted for both vertical and rotary movement, of a motor, a shaft having a pinion therein, a horizontal rack engaging the pinion and connected to be reciprocated by the motor, a lifting lever for the valve, means on said shaft for actuating the lifting 120 lever, a crank member connected to the valve, and means operated by the motor for engaging and actuating the crank member after the valve has been raised by the lifting lever, substantially as described.

125 4. The combination with a gas-reversing valve arranged to be first lifted and then rotated, of a motive cylinder, lifting mechanism for the valve connected to said cylinder, and a valve-rotating device arranged to 130

be operated by the cylinder after the valve has been lifted, together with oppositely movable air valves, and connections between said valve and the motive device, substantially as described.

5. The combination with a gas-reversing valve arranged to be first lifted and then rotated, of a motive cylinder, lifting mechanism for the valve connected to said cylinder, and a valve-rotating device arranged to be operated by the cylinder after the valve has been lifted, together with oppositely movable dampers and operating connections between the dampers and the motive device, substantially as described.

6. The combination with a rotary gas-reversing valve, of a bifurcated crank member connected to the valve, a motive cylinder, and a reciprocating member operated by said cylinder and arranged to alternately engage the two arms of said crank member, substantially as described.

7. The combination with a vertically movable and rotatable reversing valve, of a double-acting cylinder, valve-lifting mechanism arranged to be first actuated by the cylinder, and a bifurcated valve-rotating device connected to the shaft of the valve and arranged to be operated by the cylinder after the valve has been lifted, substantially as described.

8. The combination with a vertically movable and rotatable reversing valve, of a motive device, a reciprocating member actuated by said device, a shaft arranged to be rotated by the reciprocating member, cam-and-lever valve-lifting mechanism actuated by said shaft, and a crank member attached to the valve shaft and arranged to be operationally engaged by the reciprocating member after the valve has been lifted, said crank

member being normally disconnected from the reciprocating member and arranged to be operated by moving contact therewith; substantially as described.

45

9. The combination with a vertically movable and rotatable reversing valve, of a double-acting cylinder, a reciprocating rack bar connected to the piston of the cylinder, a shaft arranged to be rotated by the rack bar, cam-and-lever valve-lifting mechanism actuated by the rotary shaft, a crank member attached to the valve shaft, and also arranged to be engaged by the rack bar after the valve has been lifted, a pulley on the valve shaft, a flexible member passed around the pulley, and two oppositely movable valve members connected to opposite end portions of the flexible member, substantially as described.

60

10. The combination with a vertically movable and rotatable reversing valve, of a double-acting cylinder, a reciprocating rack bar connected to the piston of the cylinder, a shaft arranged to be rotated by the rack bar, cam-and-lever valve-lifting mechanism actuated by the rotary shaft, a crank member attached to the valve shaft, and also arranged to be engaged by the rack bar after the valve has been lifted, a pulley on said rotary shaft, a flexible member passed around the said pulley, and two oppositely acting dampers connected to opposite end portions of the flexible member, substantially as described.

75

In testimony whereof, I have hereunto set my hand.
